METHOD AND APPARATUS FOR COILING WIRE
Ralph H. Wise, P.O. Box 356, Grand Haven,
Mich. 49417
Filed Jan. 30, 1963, Ser. No. 255,735
6 Claims. (Cl. 72—140)

This invention relates to a method and apparatus for continuously producing a dead helical coil of wire or similar filament.

When helical coils are formed merely by pushing the wire endwise through a forming tool having a helical groove of the diameter and pitch of the desired coil, the coil necessarily rotates about the axis of the helix as the coil is being formed. This produces what is termed a live coil. If the coil is to be produced continuously in indefinite lengths, this requires either an orbiting supply coil of wire, or an orbiting take-up spool, or both. This requires an awkward and expensive machine to produce any extensive length of large diameter helix. Otherwise the formed coil must be cut into short lengths because it is impractical to rotate about its own axis a coil of indefinite length.

This invention has among its objects to produce continuously indefinite lengths of dead helical coil by which is meant a coil which does not rotate about its axis as it is discharged from the machine. This makes it possible to produce indefinite lengths of helical coil which can be progressively wound on a non-orbiting drum as the coil is formed.

It is another object of the invention to provide an improved, simple, compact and economical apparatus which will continuously produce coils of helical wire from a non-orbiting supply.

Still another object is to provide an improved forming machine which can readily be adapted or adjusted to produce coils of different diameters and of different pitches.

Still another object is to provide an improved forming tool which can be adjusted to make helical coils of different diameters.

Other objects and advantages of the invention will be apparent from the following description and claims, reference being made to the accompanying drawings forming part of the specification, in which each reference character, wherever it occurs, always refers to the same part.

In the drawings:

FIGURE 1 is a side elevation of one form of machine for forming a helical coil according to the invention.

FIGURE 2 is an end elevation of the machine shown in FIGURE 1.

FIGURE 3 is a perspective view of a helical coil emerging from the machine as seen from the plane represented by the line 3—3 in FIGURE 1.

FIGURE 4 is an enlarged schematic perspective view of a wire coiling tool suitable for use in the machine of FIGURE 1.

FIGURE 5 is an enlarged section on the line 5—5 of FIGURE 4.

FIGURE 6 is an elevation partly in section of a forming tool for making helical coils of different diameters.

FIGURE 7 is an end elevation of the tool as seen from the plane represented by the line 7—7 of FIGURE 5.

Before explaining the invention in detail, it is to be understood that the invention is not limited to the particular construction nor arrangement described herein or shown in the accompanying drawings, which are for illustration only, since the invention can be embodied in other forms and can be practised or carried out in various ways. Also it is to be understood that the phrase-

ology or terminology used herein is only for the purpose of description and illustration and does not constitute a limitation of the invention.

Referring to FIGURE 4, a wire 10 is fed along its axis from left to right by a pair of feed rolls 12 and through a forming tool, generally designated by 14. The forming tool has a groove 16 in one side which is substantially filled by the wire being fed. A plate 18 is secured to the tool in suitable manner to close the groove, and provide a hole through the tool and fitting the wire. The tool includes a portion 20 which is disposed substantially axially of the wire and a portion 22 which is formed into a helix. The groove 16 runs continuously from one end of the forming tool to the other so that in the portion 22 the groove is of the form, diameter and pitch of the helix in the coil to be made. In the portion 22 the groove need not be covered by the plate 18 because in this portion of the tool the groove is on the inside of the material and the wire is held against the groove and forced against the bottom of the groove by the force which feeds the wire through the forming tool.

The apparatus as above described produces a live helical coil of wire which rotates about its axis as it is being formed, appearing to be screwing out of the tool. In order to make a dead coil, that is, one which does not rotate, the tool 14 is rotated about the axis of the wire 10 and in the sense of rotation opposite to the sense in which the coil tends to rotate as it emerges from the tool. This opposite rotation is synchronized with the speed of the feed rolls for the length of the wire which produces a given diameter of helix so that the tool is turned reversely once for each convolution of the helix being formed. This twists the wire once reversely about the axis of the wire itself for each convolution of the helix being formed and this twisting operation combined with the coiling of the wire into a helix produces a dead coil which can be formed in indefinite lengths and wound upon a non-orbiting take-off spool.

The pressure of the feed rolls 12 upon the wire prevents the wire from being twisted prior to its entry to the feed beyond the nip of the rolls, and the bend in the helical groove at the beginning of the portion 22 of the tool serves as a gripping point for the twisting.

FIGURE 1 shows one form of apparatus for performing the process described. This includes a supply spool 30 arranged to rotate about its own axis 32 to supply wire tangentially from the spool without twisting. The spool is mounted on a stationary frame 34. The feed rolls 12 are driven through suitable gearing, as will be explained, from any suitable motor 36 mounted on the frame to draw the wire through a series of straightening rolls 38 and a straightening guide 40 which may consist of mating grooved plates urged together under any desired pressure by adjusting screws 42. The wire after passing the nip of the feed rolls 12 may be pushed through another guide 44 into the forming tool 14 which is constructed as has been previously described in connection with FIGURE 4. The guide 44 is to keep the wire straight and prevent its kinking as it is pushed from the rolls 12 into forming tool 14. The guide 44 is constructed so that twisting of the wire about its axis is permitted between the plates of the guide 44.

The forming tool 14 is mounted in a quill 46 slideable, but not rotatable in a drive tube 47 mounted in bearings 48 and rotated by a belt 50 from the motor 36. The tube 47 is geared to a countershaft 52 by gears 54, 56. The countershaft drives a gear 58 which drives the feed rolls 12 through a variable speed transmission 60 indicated schematically in FIGURE 2. The gearing and transmission are so arranged that the rolls 12 feed a

length of wire equal to the length contained in one convolution of the helix during the time that the forming tool 14 makes one rotation reversely about its axis. This rotational action produces one complete twist in the wire between forming tool 14 and rolls 12, this twist occurring between the plates of guide 44.

The diameter of the groove 16 about the axis of the wire 10 determines the pitch and diameter of the helix. As long as the forming tool 14 rotates in the opposite hand direction to that of the helix and at a rate of rotation providing one twist in the wire 10 for each convolution of the helix (which may be one twist in the wire between the beginning of the section 22 of the forming tool shown in FIGURE 4 and the nip of the rolls 12) the formed helix will come out dead and will not rotate about its axis. A change in diameter of the helix being formed requires a different length of wire to be fed for each convolution of the helix. This change of the length of the wire supplied to form each helix is accomplished by adjusting the rate of the transmission to feed the length of the wire desired. The feeding of a different length of wire is accomplished by changing the speed ratio of the transmission 60 in FIGURE 2 so that for each rotation of the forming tool 14 the driving rolls 12 feed a length of wire corresponding to the length of wire in each convolution of the new diameter. Regardless of the diameter of the helix being formed, only one rotation of the forming tool 14 is required per convolution. Therefore only one twist in the wire will occur between forming tool 14 and feed rolls 12 regardless of the distance the tool 14 and the rolls 12 may be spaced apart.

In order to avoid having to replace the forming tool whenever a helix of different diameter is to be made, the invention includes the design of forming tool shown in FIGURES 6 and 7. This is suitable for making helices of different diameters but of the same pitch. In FIGURE 6 14' represents a four jaw chuck, which except for certain modifications of the jaws themselves, which will be described, is constructed in known manner. There are four tapered jaws A, B, C and D adjusted by a circular rack 72 and pinion key 74 against an internal conical annular cam 76 to adjust the diameter enclosed by the interior surfaces of the jaws. One jaw A is extended as shown in FIGURE 6 and grooved at 16' corresponding to the groove 16 in FIGURE 5.

This groove has a substantially axially extending portion 20' extending substantially axially of the wire and a coaxial helical portion 22'. This helical portion does not include a complete convolution of the helix as does the helical portion 22 in FIGURE 4, but as shown in FIGURE 7 includes part of one convolution of the helix which directs the wire 10 which could be fed from feed rolls (not shown) but which could be located at the right of FIGURE 6, and correspond to rolls 12, to the jaw B. The appropriate part of the groove 16' in the jaw A is covered by a plate 18. Each of the jaws B, C and D has formed on its inner face a helical groove 78 having an axis 80. Each end of each groove 78 is bell-shaped as shown to accommodate the wire when forming helices of different diameters. Each groove 78 has a throat between the bell-shaped ends which conforms to the diameter of the wire being worked. The wire is fed into the groove 16' and successively through the grooves 78 in the jaws B, C and D. This forms a helix of a pitch determined by the axial spacing of the grooves 78 and of a diameter determined by the radial spacing of the jaws A, B, C and D. It is contemplated that this forming chuck will be placed in the quill 46 of FIGURE 1 which will be axially adjusted in the drive shaft 47 according to the diameter of the helix to be formed.

Preferably each of the jaws has a circumferential groove 82 to receive a sizing ring 82A against which the jaws are held by the cam 76 to hold the jaws accurately and positively in spaced relationship to produce the desired diameter of coil. A different ring 82A is inserted

for each diameter of helical size. The grooves 82 are positioned so that the sizing ring 82A does not interfere with the wire 10.

I claim:

- 5 1. Apparatus for forming a helical coil of wire comprising in combination forming means having an inside helical groove having a pitch corresponding to one hand of rotation, said forming means being mounted for rotation about the axis of said groove, means for continuously feeding wire in the direction of its length along said helical groove, means for preventing rotation about its axis of the wire being fed up to a fixed point ahead of said helical groove, means for rotating the forming means in the opposite hand of rotation at a rate providing one rotation during the time one convolution of the helix is being formed and means for changing the rate of wire flow to form different diameters of helices.
- 10 2. Apparatus for forming a helical coil of wire comprising in combination forming means having an inside helical groove having a pitch corresponding to one hand of rotation, said forming means being mounted for rotation about the axis of said groove, means for continuously feeding wire in the direction of its length along said helical groove, means for preventing rotation about its axis of the wire being fed up to a fixed point ahead of said helical groove, means for rotating the groove about its axis in the opposite hand of rotation at a rate of one rotation of the groove during the time one convolution of the helix is being formed, and means for changing the rate of wire flow for a different forming tool.
- 15 3. Apparatus for forming a helix of wire comprising in combination a pair of feed rolls for continuously feeding wire in the direction of its length and for preventing rotation of the wire about its axis, means for rotating the feed rolls, means for having a helical groove in its inner wall for forming the wire into a helix at a point separated from the feed rolls, means for rotating the forming means connected to the means for driving the feed rolls to provide a fixed speed ratio between said two rotating means and means for changing said fixed ratio to provide a different speed ratio between the two driving means.
- 20 4. An adjustable chuck for forming a helical coil comprising in combination a plurality of axially disposed jaws arranged to define a cylinder, and means for radially adjusting the jaws to define different diameters, each of the jaws having an open groove on its inside face, said grooves being located along the trace of a helix having one hand of rotation, one of the jaws extending axially beyond the others and having a portion disposed along the axis of the chuck, said axially disposed portion having a generally axially extending hole for receiving a wire and communicating with the groove in said one jaw, means for continuously pushing a wire into said hole and through all of said grooves, and means for continuously rotating the chuck about its axis in the opposite hand of rotation.
- 25 5. An adjustable chuck for forming a helical coil comprising in combination a plurality of axially disposed jaws arranged to define a cylinder, and means for radially adjusting the jaws to define different diameters, each of the jaws having an open groove on its inside face, said grooves being located along the trace of a helix having one hand of rotation, one of the jaws extending axially beyond the others and having a portion disposed along the axis of the chuck, said axially disposed portions having a generally axially extending hole for receiving a wire and communicating with the groove in said one jaw, means for continuously pushing a wire into said hole and through all of said grooves, and means for continuously rotating the chuck about its axis in the opposite hand of rotation.
- 30 6. Apparatus for forming a helical coil of wire comprising in combination a frame, a supply spool, a plu-

rality of straightening rolls, a pair of straightening guides, a rotatable forming tool having a continuous groove therein including a straight portion and a curved portion of helical formation, a drive tube, feed rolls between said guides for feeding a wire from said spool over said straightening rolls, through said guides and forming tool, means for driving said drive tube and feed rolls and variable speed means for controlling the speed of said feed rolls.
